Phyllis B. Askew, Meriden, Conn., assignor to R. Wallace & Sons Manufacturing Company, Wallingford, Conn., a corporation of Connecticut

Application July 5, 1952, Serial No. 20,485

Term of patent 3½ years

(Cl. D54—12)

To all whom it may concern:

Be it known that I, Phyllis B. Askew, a citizen of the United States of America, residing at Meriden, county of New Haven, and State of Connecticut, have invented a new, original, and ornamental Design for a Spoon or Similar Article, of which the following is a specification, reference being had to the accompanying drawing, forming part thereof.

In the drawing:

Fig. 1 is a front elevational view of a spoon, showing my new design;

Fig. 2 is a side elevational view thereof;

Fig. 3 is a rear elevational view thereof;

Fig. 4 is a cross-sectional view of the handle taken at line 4—4 of Fig. 1; and

Fig. 5 is a cross-sectional view of the handle taken at line 5—5 of Fig. 1.

Fig. 6 is a cross-sectional view of the handle taken at line 6—6 of Fig. 1.

I claim:

The ornamental design for a spoon or similar article, substantially as shown.

PHYLLIS B. ASKEW.
